UNITED STATES PATENT OFFICE.

HARRY D. LILLIBRIDGE, OF ZANESVILLE, OHIO, ASSIGNOR TO AMERICAN ENCAUSTIC
TILING CO., LTD., OF ZANESVILLE, OHIO, A CORPORATION OF NEW YORK.

PAPER CONTAINER.

Application filed February 4, 1921. Serial No. 442,431.

To all whom it may concern:

Be it known that I, HARRY D. LILLIBRIDGE, a citizen of the United States, residing at Zanesville, in the county of Muskingum and State of Ohio, have invented a certain new and useful Improvement in Paper Containers, of which the following is a specification.

This invention is a service device of that kind intended to be set partially within a wall, or other surface, of a room, such as a bath room, said device constituting a section or permanent part of the wall surface and being exposed, at least partially, for convenient access to the material contained therein.

More particularly, the device is intended to be used for dispensing toilet paper, the same being in roll form.

The object in view is to supply a roll paper holder of a sanitary character adapted to be partially encased by the wall of a room and affording means for containing the roll paper so as to house the latter from the accession of moisture and dust, provision being made for withdrawing the material at will and for reloading the holder easily when the supply shall have become exhausted.

The container may, of course, be constructed of any material suitable for the purpose, but for sanitary purposes and particularly when used in bath rooms, it is preferred to employ ceramic material the exposed surfaces of which are coated with a suitable glaze.

In a practical embodiment, the container in cross section is arched so as to conform, at least partially, to the contour of the roll material, and said container is provided with an external rib or flange in its top and two ends, all parts of said rib being in the same vertical plane.

The rib or flange provides means for determining with precision the position to be occupied by the container when inserted in the wall, the tile surface of which is laid in abutting contact with the container at the ends, top and bottom thereof, whereby the container may be said to be "built in" the wall so that the rear arched portion of said container extends into and is encased by the wall.

At the upper front side, the container is provided with an opening through which access is attainable to the chamber adapted

for the storage of the roll material. Projecting forwardly from the wall locating rib or flange, is a member curved in cross section and constituting an extension of the back wall, said member forming the bottom of the container and said member projecting forwardly beyond the flange or rib. The member protrudes from the wall line, and in it is provided a delivery slot through which extends the free end portion of the roll material, so that the slot acts as means for the delivery of the material and said slot being separate from the opening in the upper exposed front of the container.

Other functions and advantages of the invention will appear from the following description taken in connection with the drawings, wherein—

Figure 1 is a perspective view of a roll holder or container embodying the invention.

Figure 2 is a horizontal cross section on the line 2—2 of Figure 3 showing the holder partially encased by the wall.

Figure 3 is a vertical cross section on the line 3—3 of Figure 2 looking in the direction of the arrow, the wall surface being indicated.

The holder or container A is composed of a single piece of material, and in the form shown it comprises end walls a, b, a rear wall c, a rib or flange d, and a member B, the latter being continuous with the back or rear wall c. The end walls a, b are flat and positioned in parallel relation, the contour of the marginal portions of said end walls conforming to the shape of the rear wall c and the member B so that the parallel walls a, b act as closures for the ends of the holder or container. The rear wall c is curved in vertical cross section, and the member B is likewise curved in cross section, the parts c, B being continuous for all practical purposes and conforming substantially to the cross sectional form of the roll material adapted to be stored within the container and to be served from it as required.

The rib or flange d extends continuously around the top and two ends of the holder, all parts of said rib being in the same plane and said rib being external to the holder and protruding a desired distance therefrom.

Member B extends forwardly from the rib d at the ends and front of the holder, the upper front side of said holder being provided with an opening C of such size

as will permit the roll material to be introduced within the chamber of the holder, the bottom of said opening C being bounded by the top edge of the member B.

5. In the curved bottom of the forwardly extending member B is a slot D, the same extending crosswise of the protruding member and below the opening C in the holder.

For sanitary purposes, the entire holder is 10 composed of ceramic material molded in one piece and the exposed surfaces of which are coated with an impervious glaze, although it will be understood that any material suitable for the purpose may be used in the 15 manufacture of the holder.

The article is adapted to constitute a portion or section of a wall, usually a tile wall commonly used in bath rooms, etc. The rear part of the holder is inserted into the wall, 20 or a cavity therein, and the holder is laid in cement with the other tiles of the wall, the line of which is indicated at W. Preferably, the tiles are laid in abutting relation to the protruding ribs d at the ends 25 and top of the holder, whereby the rib determines with precision the position on the wall to be occupied by the holder.

The member B protrudes for a substantial distance from the exposed surface of the 30 wall, so that the opening C is fully exposed for the introduction of the roll material. Said roll material is thus effectively housed within the holder, with the free end of said material passing through the slot D and 35 normally hanging free therein, so that said free end can be grasped easily for withdrawing a desired quantity of the material without removing the roll material from the holder.

40. Having thus fully described the invention, what I claim as new and desire to secure by Letters Patent is:

1. A holder for roll material comprising a chambered container provided on its ends 45 and at the top with an external locating rib all the parts of which are in the same vertical plane, an arcuate back member extend-

ing continuously from the top of the container along the rear and the bottom and beyond the external rib to produce a member 50 protruding forwardly of the vertical plane of the axis of generation of said arcuate back member, the rear and bottom of the container being closed by said continuous arcuate wall and the upper front part 55 of said container being open from the top to the forward edge of the arcuate member, and a delivery slot positioned in said forwardly protruding member and below the open front part of said container. 60

2. A holder for roll material embodying parallel side walls and a continuous wall of arcuate formation extending from the top of the holder continuously along the rear and the bottom, the forward edge of said 65 continuously curved wall extending beyond the vertical plane of the top edge of the holder and producing a forwardly protruding member which is continuous with the rear and the bottom of the holder, the upper 70 front part of the holder being open from the top edge to the forward edge of said curved wall, and a delivery slot positioned in said forwardly protruding member below the open front side of the holder and forwardly 75 beyond the vertical plane of the axis of generation of said arcuate continuous wall.

3. A holder for roll material comprising a one piece container open at the upper front part and provided intermediate the front 80 and the rear with a vertical locating rib, the rear and bottom of the container being of arcuate formation and said bottom projecting upwardly and forwardly beyond the locating rib to produce a protruding member adapted to serve as a barrier to the displacement in one direction of roll material, and a delivery slot positioned in the forwardly protruding barrier member and below the opening in the front upper portion of the 85 container. 90

In testimony whereof I have hereto signed my name this 6th day of January, 1921.

HARRY D. LILLIBRIDGE.
